UNITED STATES PATENT OFFICE.

AZEL GAY, OF ROCHESTER, NEW YORK, ASSIGNOR TO MULTIPOST COMPANY, INCORPORATED, OF ROCHESTER, NEW YORK, A CORPORATION OF NEW YORK.

STAMP-AFFIXING MACHINE.

Application filed April 5, 1928. Serial No. 267,706.

The invention relates to a stamp affixing machine, with particular reference to the type of mechanism in which a downwardly travelling plunger serves to moisten an envelope, sever a stamp from a roll, and affix the stamp to a moistened portion on an envelope, and has for its particular object to afford simplified and efficient means for controlling the feed of water used in moistening an envelope prior to affixing a stamp thereto.

In a more detailed aspect, the invention contemplates utilizing an efficient, practicable and durable mechanism within the water compartment cooperating with the actuating plunger in such a way as to lend to the parts long wearing qualities and to make it difficult for the mechanism to get out of order, or to operate improperly.

Another object of the invention is to provide compact mechanism that permits quick and easy adjustment of the water ejector so as to vary the amount of water discharged on to an envelope.

To these and other ends, the invention consists in the construction and arrangement of parts that will appear clearly from the following description when read in conjunction with the accompanying drawings, the novel features being pointed out in the claims following the description.

In the drawings:

Figure 1 is a side view, partially broken away, showing the application of the invention to a known type of stamp affixing machine;

Figure 2 is a bottom plan view;

Figure 3 is a sectional view on line 3—3 of Figure 1;

Figure 4 is a front elevation of the water ejecting mechanism;

Figure 5 is a side elevation of the same with the water ejector in its retracted position just before release to discharge water;

Figure 6 is a side elevation looking in the opposite direction from Figure 5 and showing the water ejector in normal position or closed, and with the contact member in its retracted relation to the water ejector;

Figure 7 is a side view of the cam, and

Figure 8 is an end view of the same. Referring more particularly to the drawings, in which like reference numerals refer to the same parts throughout the several views, 1 designates the usual housing of a stamp affixing machine of this general type,

while 2 is the operating plunger for operating the conventional stamp feeding and severing devices as it travels downwardly, 3 being the operating handle on the plunger, and 4 the foot that affixes the stamp upon the surface of an envelope.

Suitably attached to the plunger 2, as for instance by means of a plate 5, is a rack 6 engaging a pinion 7 that is mounted on an arbor 8 suitably journalled in a wall 9 of the water compartment 10. The arbor 8 carries a pin 11, these parts constituting the actuating means for the water ejecting mechanism now to be described, and while the rack and pinion operating means has been found quite efficient for the purposes of the invention, it is to be understood that other forms of mechanism may be substituted for the rack, pinion and rotary arbor just described to effect the necessary movement of the water ejecting mechanism.

The water compartment includes opening 12 in the wall 9, as usual in this type of construction, and the water ejector comprises a wide lower portion 13 having the upturned end 14 for holding a pad 15, and a reduced upper portion 16 having ears for pivotally engaging a post 17 that is fixedly mounted on a base 18 carried by the wall 9. The water ejector 13 is held in its normal position as illustrated in Figures 4 and 6 by means of a suitable spring coiled around the post 17 having its free ends 19 in engagement with the wall 9 and its portions 20 engaging the edges 21 of the lower portion 13 of the water ejector and thereby moving the latter toward the openings 12.

The water ejector is operated by the aforementioned pin 11 through a contact member that is movably mounted with relation to the water ejector so as to move the latter when travelling in one direction and to be movable independently of the water ejector when the pin 11 is travelling in the direction induced by the upward movement of the rack 6. The construction and arrangement of this contact member will now be described.

The contact member comprises a suitable plate 25 having ears or side walls 26 which are also pivoted on the aforementioned post 17. Permanently attached to the plate 25 is a support 27 having a cam portion 28 at its outer end and a threaded opening 29 that receives the threaded adjusting pin 30, which engages the water ejector as shown in Figure 110.

5. The plate 25 has its lower end bent upon itself to receive and hold a pin 31 which forms a support for a spring 32, one end of which is designated at 33 and engages the 5 lower part of the water ejector while the opposite end 34 engages a slot in the adjusting pin 30, thus serving to hold said pin in adjusted position.

The spring 32 acts to retain the contact 10 member, including the plate 25 and cam 28 just described, in their normal relations to the water ejector with adjusting pin 30 in contact with the upper part of the water ejector, as shown in Figure 5, so that when the arbor 15 8 and pin 11 are turned clockwise with reference to Figure 4, the pin 11 engaging cam 28 on the contact member will rock the latter and with it the water ejector to the position shown in Figure 5.

20 As soon as the pin 11 passes out of engagement with cam 28 upon further downward movement of the rack 6, the contact member and water ejector are released and the spring portions 19 and 20 throw the water ejector 25 quickly to normal position and cause the proper amount of water to be discharged through the openings 12. The amount of water thus discharged can be varied by adjustment of the pin 30 which permits the cam 30 28 to be positioned closer to or farther away from the water ejector, and in this manner causing the water ejector to be moved to a greater or less degree as it is opened by the pin 11 through cam 28.

35 Upon the return or upward travel of the rack 6 as the plunger is restored to normal position, pin 11 engages the rear side of cam 28, having reference to Figure 4, causing the contact member to rock on its axis away from the water ejector, as in Figure 6, against the action of spring 32, and without any movement of the water ejector. As soon as the pin 11 passes out of engagement with the cam 28, the contact member is restored to initial 40 position by the spring 32 and the parts are then in readiness for another operation.

50 While the invention has been described with reference to certain structural details, it is not limited to the precise form or arrangement herein disclosed, and this application is intended to cover such modifications or changes as may come within the intent of the improvement or the scope of the following claims.

55 I claim:

1. In a stamp affixing machine, the combination with a water compartment, of a water ejector movable in the compartment, a pivoted contact member that engages and moves the water ejector in one direction and is movable independently of the water ejector in the opposite direction, and actuating means 60 cooperating with the contact member.

2. In a stamp affixing machine, the combination with a water compartment, of a wa- 65

70 ter ejector movable in the compartment, a contact member that moves the water ejector in one direction and is movable independently of the water ejector in the opposite direction, a cam carried by the contact member, and an actuating device engageable alternately with opposite sides of the cam.

75 3. In a stamp affixing machine, the combination with a water compartment, of a water ejector movable in the compartment, a contact member that engages and moves the water ejector in one direction and is movable independently thereof in the opposite direction, actuating means cooperating with the contact member, and adjustable means for so varying the relation of the contact member and water ejector to vary the throw of the latter.

80 4. In a stamp affixing machine, the combination with a water compartment, of a water ejector pivoted in the compartment, a contact member pivoted coaxially with the water ejector, a pin carried by one of said pivoted parts and adjustably engaging the other of said pivoted parts, and actuating means 85 cooperating with the contact member.

90 5. In a stamp affixing machine, the combination with a water compartment, of a water ejector pivotally mounted in the compartment, a contact member pivoted coaxially with the water ejector, a pin carried by the contact member and adjustably engaging the water ejector, said pin having a slot in one end, a spring carried by the contact member and having one end anchored in said slot of the pin to hold the latter in adjusted position, and actuating means 95 cooperating with the contact member.

100 6. In a stamp affixing machine, the combination with a water compartment, of a water ejector pivotally mounted in the compartment, a contact member pivoted coaxially of the water ejector, said contact member acting when moved in one direction to move the ejector and movable in the other direction independently of the ejector, a pin carried by the contact member and adjustably engaging the water ejector to permit varying the throw of the latter, a cam carried by the water ejector, and an actuating member movable alternately 110 on opposite sides of the cam.

115 7. In a stamp affixing machine, the combination with a water compartment, of a water ejector pivotally mounted therein, a contact member pivoted coaxially of the ejector, said contact member serving to move the ejector when operated in one direction and movable independently of the ejector in the opposite direction, a cam carried by the contact member, and an oscillatory arbor carrying a 120 pin engageable alternately with opposite sides of said cam.

125 8. In a stamp affixing machine, the combination with a plunger and water compartment, of a water ejector pivotally mounted in 130

the compartment, a contact member pivoted coaxially of the ejector, said contact member serving to operate the water ejector when moved in one direction and being movable independently of the water ejector in the opposite direction, a cam carried by the contact member, an oscillatory arbor, a pin on the arbor alternately engaging opposite sides of said cam, a pinion carried by the arbor, and a rack carried by said plunger having engagement with the pinion.

9. In a stamp affixing machine, the combination with a plunger and water compartment, of a water ejector pivotally mounted in the compartment, and operating means

for the water ejector including an oscillatory arbor, a pinion carried by the arbor, and a rack carried by the plunger and having engagement with said pinion.

10. In a stamp affixing machine, the combination with a water compartment, of a swing-²⁰ ing water ejector in said compartment, a contact member that engages and moves the wa-²⁵ ter ejector in one direction and moves inde-
pendently thereof in the other direction, and revoluble means for actuating the contact member.

In witness whereof, I have hereunto signed my name.

AZEL GAY.
